UNITED STATES PATENT OFFICE.

ARTHUR HALE, OF NEW YORK, N. Y.

SLIPPER WITH REMOVABLE COUNTER.

1,027,249.

Specification of Letters Patent.

Patented May 21, 1912.

Application filed September 25, 1911. Serial No. 651,243.

To all whom it may concern:

Be it known that I, ARTHUR HALE, a citizen of the United States, residing at New York, in the county of New York and State 5 of New York, have invented certain new and useful Improvements in Slippers with Removable Counters; and I do hereby declare the following to be a full, clear, and exact description of the invention, such as 10 will enable others skilled in the art to which it appertains to make and use the same.

This invention relates to sanitary foot wear, and especially to slippers, and has for its object to provide a foot covering in 15 which the counters or the middle sole, or both may be readily removable in order that the other portions of the shoe or slipper may be washed when desired.

To these ends the invention consists in the 20 novel details of construction, and combinations of parts more fully hereinafter disclosed and particularly pointed out in the claims.

Referring to the accompanying drawings 25 forming a part of this specification in which like numerals designate like parts in all of the views:—Figure 1 is a perspective view of a foot covering, made in accordance with my invention; Fig. 2 is a longitudinal sectional view of the parts shown in Fig. 2; and Fig. 3 is an enlarged detail sectional plan view of a portion of the parts shown in Fig. 2.

1 represents the upper of the foot covering or slipper, 2 the inner sole thereof, and 3, the outer sole. The inner and outer soles are secured together along their edges as by stitching 4, Fig. 1, leaving a pocket between the same. The inner sole 2 is further provided with a slit or opening 5 preferably near the heel portion in order that a stiffening member or middle sole 6 may be readily inserted into and withdrawn from the pocket between the inner and outer soles. The slipper is further provided with a counter portion 7, composed of an inner wall 8 and an outer wall 9, providing a pocket between the same for the reception of a stiffening counter member 10, as shown. The said

walls 8 and 9 are secured together along 50 their edges by any suitable means, as by the stitching 16, best illustrated in Fig. 1. The inner wall 8, of the counter portion 7, is likewise provided with an opening or slit 11, through which the counter member 10 55 may be readily inserted into the pocket between the walls 8 and 9, and may be as readily withdrawn when it is desired to wash the parts.

13 represents any suitable border for the 60 foot covering, and the parts may be made of any suitable material, but a washable fabric is preferred. When it is desired to wash the parts, the stiffening member 6 or middle sole is readily withdrawn through 65 the slit 5, and the stiffening counter member 10 is readily withdrawn through the slit or opening 11, whereupon the upper and other portions of the slipper may be readily washed, dried, and the stiffening members 70 reinserted.

It is obvious that those skilled in the art may vary the details of construction and the arrangement of parts without departing from the spirit of my invention, and therefore I do not wish to be limited to the above disclosure except as may be required by the 75 claims.

What I claim is:—

1. A foot covering provided with a 80 counter portion having inner and outer walls secured together to form a pocket, and one of said walls providing an opening into said pocket through which a stiffening member may be readily inserted and withdrawn, 85 substantially as described.

2. A foot covering provided with a counter portion having inner and outer walls secured together and forming an open mouth pocket; and a stiffening member located in said pocket, substantially as described. 90

In testimony whereof, I affix my signature, in presence of two witnesses.

ARTHUR HALE.
